ATTORNEYS

UNITED STATES PATENT OFFICE.

CHARLES O. F. YOUNGSTROM, OF PHOENIX, ARIZONA TERRITORY.

DESIGN FOR A CASING FOR WATER-HEATERS.

SPECIFICATION forming part of Design No. 31,810, dated November 7, 1899.

Application filed August 2, 1899. Serial No. 725,928. Term of patent 14 years.

To all whom it may concern:

Be it known that I, CHARLES O. F. YOUNGSTROM, of Phoenix, in the county of Maricopa and Territory of Arizona, have invented and produced a new and original Design for a Casing for Water-Heaters, of which the following is a full, clear, and exact description.

Reference is to be had to the accompanying drawing, forming part of this specification, in which the figure is a perspective view illustrating my design.

As shown in the drawing, the design consists in the casing A, which is approximately in the form of an inverted frustum of a cone, the top B extending beyond the base of the frustum and one edge of the top being curved,

while the opposite edge is straight. A collar C rises from the top, and a collar D appears at the opposite end of the casing, and between the top and bottom of the latter appear openings E and F.

The leading feature of the design consists in the design shown in the accompanying illustration.

I claim—

The design for a casing for water-heaters herein shown and described.

CHARLES O. F. YOUNGSTROM.
